PITTSFIELD SPARK COIL COMPANY, OF DALTON, MASSACHUSETTS, A CORPORATION.

COMBINED DISTRIBUTER AND TIMER DEVICE.

No. 928,209.

Specification of Letters Patent.

Patented July 13, 1909.

Application filed November 13, 1908. Serial No. 462,413.

To all whom it may concern:

Be it known that we, THEODOR M. MUELLER, a subject of the Emperor of Germany, and ALBERT JACOB, a citizen of the United States of America, residing at Dalton, in the county of Berkshire and State of Massachusetts, have invented new and useful Improvements in Combined Distributer and Timer Devices, of which the following is a specification.

Our present invention relates to improvements in combined distributers and timers, as used in electrical ignition systems for igniting the charge of internal combustion or vapor engines.

The object of the invention is to produce a device that is simple and reliable in construction and one that may be readily changed or converted into a simple distributer without reference to the timing feature; that is to say, when the device is to be used in connection with a magneto or non-vibratory coil alone, and not in connection with an induction coil of the make and break or vibratory type.

Referring to the drawings forming part of this application,—Figure 1 is a plan view of the distributer end of the device showing the binding post for receiving a high-tension terminal and also binding-posts to which the lead wires are connected to the various cylinders. Fig. 2 is a vertical sectional view on the line 2—2 of Fig. 1 clearly illustrating the internal construction of the device the parts being indicated at the moment that the distributer plate is passing one of the terminals and the resilient contact arms or fingers are in contact with the primary terminal, and Fig. 3 is a horizontal sectional view on the line 3—3 of Fig. 2 illustrating the radial arrangement of the resilient contact fingers with relation to the driving shaft and the primary terminal.

In the drawings, *a* designates the shell or casing of the device which is preferably composed of some high insulating material, as hard rubber or prepared fiber, and in the base portion thereof are located the various terminals *b* that are cast in the base portion *c* and terminate in the spark-point *d*, which in practice is preferably nickel-plated. The spring-clips *e* for receiving the lead-wires are secured to the terminals *b* in any suitable way, as riveting.

f designates a high tension terminal that

is cast in the center part of the base portion *c* and bored out to receive a coil spring *g* for the purpose of normally pressing outward the hardened ball *h* against the distributer-plate *h* that is carried by the disk-shaped distributor block *i* of insulating material shown in plan view in Fig. 1. This plate is secured to the block *i* in any suitable manner, as by means of the screw *j*, shown in Figs. 1 and 2.

The distributer-block *i* is driven by means of the tubular hub *k* that is secured to the hub portion *m* by means of the pin *n*, the part *k* being secured to the block *i* by means of the plate *o* and screw *p*.

q designates a ring that is secured to the casing *a* in any suitable manner, as by means of the dowel pins *q*¹ which are cast in the casing and secured to the ring *q* by means of the pin *q*². The bushing or sleeve *r* of insulating material is located in the ring *q*, and through the sleeve the threaded terminal *s* that carries at its inner end the contact fork *t* passes. The resilient contact fingers *v* and *w*, which are arranged to pass through the fork *t* and make contact therewith are secured on the hub portion *m*.

The fingers *v* and *w* normally are of greater width or distance apart than the opening in the fork *t* whereby when these fingers engage the fork a good electrical contact is made, and it will be observed that the fingers *v* and *w* are concavo convex or U-shaped in end elevation, as shown in dotted lines in Fig. 2.

x designates a plate that is secured to the ring *q* in any suitable manner, as by means of a slot and screw connection (not shown) whereby the position of the fingers *v* and *w* may be so arranged as to engage or leave the fork *t* at the same time that the distributer plate *h* is passing one of the points *d* of the terminals *b*.

The plate *x* is provided with a bushing or bearing surface *y* for a connecting shaft that is inserted in the bushing for driving the fingers *v* and *w* and the block *i* which carries the distributer-plate *h*.

It has not been considered necessary to show the various electrical connections and circuits in which the distributer and timer device are employed, but it may be stated that the contact fingers *v* and *w* pass through or leave the fork *t*, which is in the primary circuit, at the same time that the distributer-plate *h* is adjacent the distributer point *d*.

that is in electrical contact with the terminals *b* to which the various lead wires are connected.

If it is desired to use the distributor feature of the device alone without employing the spring finger construction *v* and *w*, it is only necessary to remove the same and drive the distributor block *i* alone, it being understood that the terminal *f* is connected to the high tension side of a magneto or other source of high voltage current, and that the current will flow from the terminal *f* through the ball and plate to the terminals *e* in succession, as readily understood.

15. The timer contacts *v* and *w* and the contact forks *t* may, of course, be employed alone without using the distributor, by simply disconnecting the distributor block *i* from the drive-shaft by removing the pin *n*.

20. It will thus be seen that we have produced a very simple and inexpensive device for carrying out the above described objects.

What we claim, is:—

1. A distributor and timer device having in combination, a base-plate, a terminal mounted therein, a distributor rotatably mounted with relation to the terminal, the distributor being provided with resilient fingers, and a fork terminal with which said

30 fingers engage during their rotation.

2. In a distributor and timer device, a rotatable member having spring or resilient

fingers secured thereto, said fingers being concavo convex in cross section, and a fork terminal with which the fingers engage during their rotation.

3. A distributor and timer device having in combination, a casing or base-piece, a high tension terminal and distributor terminals mounted therein, a rotatable block provided with conducting means in electrical contact with the high tension terminal, and a series of resilient U-shaped fingers adapted for simultaneous rotation with the block, and a fork terminal located in the path of the fingers, as described.

4. A distributor and timer device comprising a casing, distributor terminals mounted therein, a rotatable block, a conducting plate carried thereby, a terminal engaging the plate, a resilient U-shaped contact member adapted for rotation with said block, and a fork terminal member located in the path of the U-shaped contact member.

5. In a timer device, a rotatable member having spring or resilient fingers secured thereto, said fingers being concavo convex in cross section, and a fork terminal with which the fingers engage during their rotation.

THEODORE M. MUELLER,
ALBERT JACOB.
